UNITED STATES PATENT OFFICE.

JOSEPH LYONS SEARFOSS, OF PROVIDENCE, RHODE ISLAND.

DREDGING DEVICE.

SPECIFICATION forming part of Letters Patent No. 792,796, dated June 20, 1905.

Application filed April 30, 1904. Serial No. 205,838.

To all whom it may concern:

Be it known that I, JOSEPH LYONS SEARFOSS, a resident of the city of Providence, in the county of Providence and State of Rhode Island, have invented certain new and useful Improvements in Dredging Devices; and I do hereby declare that the following is a full, clear, and exact description thereof, reference being had to the accompanying drawings, and to the numerals of reference marked thereon, which form a part of this specification.

This invention relates to improvements in dredging-machines, and has for its object the construction of simple, practical, and effective means for successfully operating that style of dredging-bucket commonly known as the "clam-shell" bucket and "orange-peel" bucket or other pole-operated dredging or excavating bucket.

This invention is an improvement on my device described and illustrated in my application filed February 19, 1904, Serial No. 194,328.

The old methods heretofore employed have been unsuccessful in operating the above-mentioned class of bucket for dredging in rough water or on a hard bottom, as poles have to be used to guide the bucket while being raised and lowered, and when the bottom is at all hard the bucket has to be held down rigidly by said poles in order to make the jaws bite into the substance on which it rests. While dredging in rough water the waves raise and lower the dredging-scow, causing the bucket to be lifted clear of the bottom and then dropped down again with great force, often bending and breaking its poles or raising the boom, and its work is very unsatisfactory and in many cases impossible. When the bucket is dropped to the bottom of the river, its jaws are open to the extreme nearly at right angles to the line of the poles. As it lies on the bottom in this position it is held down by said poles, and when the bucket rests on a gravel or hard sandy bottom and the power is applied to close the jaws its edges must necessarily be forced down into the material or something above must give away and allow the poles to be forced upward. The latter result is usually the case, rendering the work of this class of bucket under these conditions

very ineffective. Then, again, it is found in practice very difficult to dig on the side of an inclined bank with the ordinary clam-shell type of bucket, as oftentimes one of the jaws only will engage the bank at a time and in closing the bucket a great side strain is necessarily brought upon the poles. To obviate this difficulty, I have hung the bucket and its actuating mechanism on a pivot at the ends of the supporting-poles, so that said bucket can swing and accommodate itself to any irregularity in the surface of the substance it must engage.

Another object of the invention is to regulate the tension or pressure on the bucket through poles, which is done by gripping or binding yokes described in my above-mentioned application.

Another object of this invention is to provide an automatically-adjustable supporting-arm which is designed to engage the bucket-poles near the water's edge and serves to stiffen and prevent said poles from bending and breaking.

The invention consists of other novel features and parts and combinations of the same, as will be fully described hereinafter and then pointed out in the appended claims.

A practical embodiment of the invention is represented in the accompanying drawings, forming a part of this specification, in which similar characters of reference indicate corresponding parts in all the views.

Figure 1 is a side elevation showing the arrangement of my improved attachments to a dredging-machine. Fig. 2 illustrates the automatic locking device on the supporting-arm. Fig. 3 is an enlarged side elevation illustrating the manner of pivotally hanging the said bucket on the end of said poles, said bucket being partly broken away. Fig. 4 is a side elevation of the same. Fig. 5 illustrates the bucket as engaging an irregular bank and being thrown off at an angle, which is possible by the use of my improved method of holding said bucket. Fig. 6 shows a detail of the brake and handle for controlling the downward tension on the boom. Fig. 7 is a plan view of the platform and the mechanism mounted thereon for gripping the poles.

In the drawings, 1 denotes the dredging-scow, which is shown in section and on which all of the operating mechanism is carried. At 2 is the boom, which is pivotally held at 3 on the collar 4, which collar is held to rotate around a hollow center plate 5, that is secured to the deck of the scow. Said boom 2 is set on an angle to the deck of said scow and supported in position from the mast 6 by the supporting-rods 7 and 8. On the outer end of this boom is a platform 9, on which is supported and secured the mechanism for gripping and holding the poles of the bucket. These bucket-poles 10 project upward through the locking mechanism on the platform 9 and are necessarily very long, so that they can drop the bucket to the bottom of the river. Secured to this platform 9 is the fixed jaw 11 of the grip-yoke, (see Fig. 7,) which is bolted to said platform. At 12 is the reciprocating jaw on the opposite side of the poles, which jaw is arranged to slide laterally in the guides 45 45 and engage or release said poles. These guides 45 are secured to either side of the platform by suitable fastenings. Guide-pins 46 46 are secured to said reciprocating jaw and extend through corresponding holes in the fixed jaw, one on either end of the same. Cranks 13 13 are mounted on the shaft 47 and are connected to the lug 48 of the reciprocating jaw 12 by the connections 49 49. At 50 is the outwardly-extending arm, on which is adjustably secured the counterbalance-weight 51. The grooved pulley 14 is mounted on 35 and fixed to the shaft 47, which shaft is supported at either end on bearings 52 52. At 16 is a pulley which is held to slide or roll on a circular track 17, located at the front end of the scow. The wire rope 15 has a turn 40 around the pulley 14 with one end fixed thereto and is led down around the pulley 16, up over the pulley 17, that is mounted on the boom 2, and back over pulley 18, thence down through the hollow center plate 5, over pulley 45 19 to the winding-drum 20. It will be observed that this flexible rope thus, arranged will draw and hold the boom down and prevent it from rising, and said rope by this arrangement will always lead fairly from the 50 center and follow the ever-changing position of the boom to act upon it squarely and draw from directly beneath it in whatever position said boom may be. The drum on which this rope is wound to receive its tension is driven from the gear 21 through the pinion 22 and is controlled in its speed and tension by the action of a suitable brake, such as that illustrated in Fig. 6, which is under the constant control of the operator. The gear 21 is mounted 55 on the main shaft 23, on which shaft is also mounted the drum 24, that controls the opening and closing of the bucket through the flexible rope 25. At 8 is an additional supporting-rod for the boom 2 to prevent said boom from 60 springing when the tension is applied on the 65

flexible rope 15 to draw said boom down or hold it from rising.

At 26 is an arm for supporting the poles to keep them from bending and breaking and may be made in any suitable form to engage 70 the bucket-poles at one end and have its opposite end adjustably supported from the boom 2. This arm may be made double, so it will straddle both the boom 2 and the tension-cable 15, or it may be made single and 75 engage one side of the boom only; but in either case it engages and supports both poles. At 27 are rings, which are attached to the outer end of said supporting-arm, one ring 80 loosely engaging each of the poles 10, so that said poles may freely slide through the same. When the bucket is down, the outer end of this arm is supported by the rope 28, which rope is fast at one end to said arm, while the opposite end passes up around the loose pulley 29 and has a counterbalance-weight 30 hung to it. When the bucket has been filled, it is raised to the surface of the water, when it engages the rings 27 in the end of arm 26, and this end of the arm then rises up with the 85 bucket and follows the movement of the same. In order to allow the said arm to rise with the bucket, I have pivoted the same on the shaft 31, (see Fig. 2,) which shaft is hung in bearings (not shown) secured to the boom. On 90 this shaft 31 is mounted and fixed the gear 32, the teeth of which engage those of the rack 33, which latter is attached to the under side of the said arm 26. At 34 is a notched disk also mounted on and fixed to said shaft 100 31. The lock-lever 35 is pivoted to the boom at 36, extending up back of the arm, and has its upper end bent off at an angle, as at 37, to rest on top of the arm 26. At 38 is a projection or tooth on said lock-lever, that engages 105 one of the notches in the disk 34. At 39 is a roll supported from the arm 40, which arm is hung on the shaft 31. This roll extends over the top of the arm to prevent the rack from rising out of mesh with the gear. 110

The construction of the bucket 41 and its operating mechanism is much the same as that of the ordinary bucket of this type, with the exception that in my improved construction I have extended the shaft 42, to which I have 115 pivotally hung the supporting-poles 11 instead of connecting them rigidly to the guide-rods 43 43. Therefore in my improved construction the bucket guide-rods and all of the attending mechanism may be swung off at an 120 angle to the poles in order that the bucket may accommodate itself to the unevenness of the surface of the soil with which it comes in contact.

The operation of the machine is further described as follows: When this type of bucket is dropped to the bottom of the river, it is 125 opened in the usual way by mechanism not shown but well understood by those skilled in their use. In closing this bucket again a con- 130

siderable power has to be exerted through the wire-rope connection 25, the strain of which naturally has a tendency to raise the bucket. Then, again, as hereinbefore described, in attempting to close the jaws of this bucket when it is resting on hard bottom, the natural tendency being to rise instead of embedding itself into the hard material, the strain is again materially increased. Under the above conditions it will be seen that a great strain must be withstood by the poles and by the boom 2, that supports the whole from its end. It is found in practice that under the severe strains to which the poles are subjected they have a natural tendency to buckle and break, to prevent which I have constructed the supporting-arm 26, which is hung at one end from the boom 2 and is automatically locked thereon from moving endwise by the mechanism above described, which arm reaches out to engage said poles as near the water's edge as practical. The bucket on being raised when reaching the surface of the water engages the arm and carries the outer end up with it. As this arm is raised the end 37 of the lock-bar 35 is also raised, withdrawing the tooth 38, which unlocks the disk 34, leaving the gear 32 free to turn, and the arm is carried forward to accommodate itself to the position of the suspended bucket. As the bucket is again lowered the arm follows it down until the counterbalance-weight 30 on the end of the suspending-cord 28 brings up against the stop. As this arm falls it naturally swings back into position, riding on the face of the gear 32. When said arm has dropped a predetermined distance, the tooth 38 on said lock-bar 35 enters one of the notches in the disk 34, and said arm is locked and securely held from an endwise movement. As before stated, said disk and gear are fixed to the same shaft 31, and when the disk is locked the gear can no longer rotate, and as the teeth in the rack, which is secured to the arm, engage those in the gear said arm is fixed from a longitudinal movement.

My invention is not restricted to the precise construction and arrangement of parts herein shown and described nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

Having thus described my invention, what I claim as new, and desire to secure by Letters Patent, is—

1. In a device of the character described, a boom, a pole-supported bucket suspended from said boom, an arm for engaging and stiffening said poles below said boom, and

means for locking said arm against an endwise movement. 65

2. In a device of the character described, a boom, a bucket, poles supporting said bucket from said boom, an arm to engage said poles below said boom and support them against bending and breaking, and means for automatically locking said arm against an endwise movement. 70

3. In a device of the character described, a boom, a bucket, poles supporting said bucket from said boom, an arm hung from said boom and engaging said poles below the outer end of said boom to support said poles against bending and breaking. 75

4. In a device of the character described, a boom, a bucket, poles supporting said bucket from said boom, an automatically-adjustable arm hung from said boom and engaging said poles below the outer end of said boom to support said poles against bending and breaking. 80

5. In a device of the character described, a boom, a bucket, poles supporting said bucket from said boom, a supporting-arm engaging said poles, said arm being supported from said boom and means for locking said arm 90 against moving endwise.

6. In a device of the character described, a boom, a bucket, poles supporting said bucket from said boom, a supporting-arm engaging said poles, said arm being supported from said boom and means for automatically locking said arm against moving endwise. 95

7. In a device of the character described, a boom, a pole-supported bucket, means whereby said poles may be locked in any desired 100 position against vertical movement and means for supporting said poles below said boom.

8. In a device of the character described, a boom, a bucket, poles supporting said bucket from said boom, means whereby said bucket 105 will automatically adjust itself to the uneven surface of the material it engages to prevent the bending and breaking of the said pole.

9. In a device of the character described, a boom, a bucket, poles supporting said bucket from said boom, means whereby said bucket will automatically adjust itself to the uneven 110 surface of the material it engages to prevent the bending and breaking of the said poles, and means for preventing said boom from rising while said bucket is being closed.

10. In a device of the character described, a boom, a bucket, poles supporting said bucket from said boom, means beneath the boom for exerting a downward tension on the outer end 120 of the boom when the bucket is being closed.

11. In a device of the character described, a boom, a bucket, poles supporting said bucket from said boom, means located beneath the boom and adapted to follow the motion of the 125 swinging boom and exert a downward tension thereon when the bucket is being closed.

12. In a device of the character described, a

boom, a bucket, poles supporting said bucket from said boom, flexible means adapted to follow the swinging motion of the same and exert a downward tension thereon when the 5 bucket is being closed.

13. In a device of the character described, a boom pivotally hung, a bucket, poles supporting said bucket from said boom, means including a pulley adapted to travel with the 10 movement of the swinging boom, a rope led

from the outer portion of said boom over said pulley for the purpose of exerting a downward tension on said boom while the bucket is being closed.

In testimony whereof I have hereunto set 15 my hand this 26th day of April, A. D. 1904.

JOSEPH LYONS SEARFOSS.

In presence of—

GEORGE CURTIS MORGAN,
CHARLES E. HICKEY.
